UNITED STATES PATENT OFFICE.

PAUL J. SMITH, OF WHEELING, WEST VIRGINIA, ASSIGNOR TO WHEELING STAMPING COMPANY, OF WHEELING, WEST VIRGINIA, A CORPORATION OF WEST VIRGINIA.

SHEET-METAL-PRESS SYSTEM.

Application filed December 6, 1921. Serial No. 520,268.

To all whom it may concern:

Be it known that I, PAUL J. SMITH, a citizen of the United States, residing at Wheeling, in the county of Ohio and State 5 of West Virginia, have invented a new and useful Improvement in Sheet-Metal-Press Systems, of which the following is a full, clear, and exact description, reference being had to the accompanying drawings, forming 10 part of this specification, in which—

Figure 1 is a side elevation showing one form of my invention;

Figure 2 is a plan view partly broken away showing the transfer chutes and parts 15 of the machines;

Figure 3 is an enlarged side elevation showing the belt transfer mechanism;

Figure 4 is a partial plan view of the second machine;

Figure 5 is a side elevation partly in section showing parts of the second machine;

Figure 6 is a cutting knife of the second machine;

Figures 7, 8 and 9 are detail sections showing the respective forms of the cap after the successive operations; and

Figure 10 is a vertical cross section through the movable blank supports of the second machine.

My invention relates to the forming of 30 caps or similar articles of sheet metal and is designed to cheapen their production and reduce the number of operators where successive operations on successive machines are 35 employed.

In the drawings in which I show a type of apparatus for forming screw-headed aluminum caps, A indicates the first machine, B the second machine and C the third 40 machine.

Heretofore in the forming of such articles an operator has been necessary for each machine, and the blanks were carried from machine to machine. The machines illustrated 45 are in their general structure well known machines and the first and third machines are of well known construction throughout. I will therefore only describe the first and third machines so far as is necessary to illustrate my invention, which relates particularly to the automatic transfer of blanks from one machine to an operating position at the next, and to the control of at least two of the machines from a single point. In my 55 system only one operator is necessary instead

of three and the blanks are transferred automatically from one machine to the next.

The first machine has a treadle control 2, this treadle also acting to start and stop the second machine B through the connections 60 shown at 3, the foot lever being fulcrumed at 4. When the operator pushes down on this foot treadle it acts through suitable clutch mechanism to start both the first and second machine into action and when the 65 foot treadle is released and raised, they stop.

The first machine acts to stamp from a sheet of aluminum the blank shown in Figure 7. The operator places the sheet on the lower die marked 5, pushes down the foot 70 treadle and the upper die 5 is forced down cutting and stamping out the blank of Figure 7. The plunger or die 6 then rises and the treadle is released, the operator moving the sheet so that the next operation of the 75 machine will cut and form another blank on again depressing the spring-lifted foot treadle. When the plunger rises, an automatic ejector forces up the cut and formed blank from the lower die. This ejector is 80 not shown, as it is a common and well known adjunct of such machines.

7 indicates an air main. Through it air flows under pressure to the pipe 8, from which branch pipes 9 and 10 lead to presses A and B. When the plunger of the press A rises, the blank cut and formed from the sheet and released by the ejector is blown by the blast of air issuing from the side orifice of the valved pipe 9, into an enclosed 90 downwardly inclined chute 11. As indicated in Figure 2, the rear upper or cover portion of this chute is preferably slotted, as shown at 12. This slot is cut to full width of the chute for a short portion of its length, as 95 shown in dotted lines in Figure 2, and a slide cover 13 can be moved back from over this portion, thereby giving access to the chute for extracting any jammed caps. As the operations take place successively, a row 100 of caps will move down through the chute 11, and the blanks of the row come successively into the range of air jets issuing from the jet pipes 14 and 15, to which the air is fed through pipe 10, which preferably has a valve control, as shown at 16. This jet or jets blows the last cap forward into the pair of hinged holders 17, shown in detail in Figures 4 and 10. Each of these holders 105 is pivoted on a stem 18, as shown in Fig- 110

ures 4 and 5, and is normally held in lifted position by a spring 19 pushing the leaves or supports up against fixed stops 20. The supporting pins for the swinging leaves are 5 preferably carried on supporting posts 24 which have a screw adjustment for height. Each of the holders 17 has a lower ledge or flange 17^a, on which the flange of the cap rests, and also has an upper spaced-apart 10 curved stop 17^b, against which the cap strikes as it is blown from the chute. These stops form a centering device to prevent the cap from passing beyond the mandrel and to hold it in operative position until forced 15 down by the cutting or trimming die. The upper die of this machine B is formed in two parts, the outer part 21 acting as a cutter, while the inner part 22 fits the base of the blank. When the plunger of 20 the B machine descends as a whole it swings the holders downwardly and apart and forces the blank down onto the die or mandrel 23. The inner plunger 22 then stops and the outer plunger 21 moves on to cut 25 off the lower flange *a* of the blank of Figure 7, thus forming the blank shown in Figure 8. When the upper plunger of the B machine rises, the spring holders rise and lift the blank into position where the blast 30 from the jet 15 will drive the blank into an inclined chute 25. The cut flange remains around the stationary plunger or mandrel 23, and as these cut, annular flanges move down one on top of the other under successive operations, the lower ones will be 35 forced down upon the cutting knife 26, thus splitting them into halves, the halves being blown by air from the jet pipes 27 into a discharge chute 28.

40 The successive caps passing down by gravity and under the air blast through chute 25, which preferably has a slotted top for inspection, drop upon an inclined belt conveyor 29. This conveyor passes over pulleys 45 on shafts 30 and 31 and may be driven by pulley 32 on one of these shafts. The upper part of this belt acts to carry the caps successively to and discharge them into the mouth of a downwardly inclined chute 33.

50 To insure their proper movement down through this chute, I also preferably provide an air pipe 34 having a valve-controlled jet 35, from which a blast enters the chute 33 through a slot at 36.

55 The machine C is of well known type having rollers 37 and 37^a which form a screw-thread on the cap. This machine, including the chute 33, may be of the ordinary type, one roller being moved away from the other 60 after each operation; but I preferably provide an air valve jet outlet 38 which will blow the threaded caps into a chute 39, leading to a receptacle 40.

The machine C is preferably driven continuously although it may be arranged in

time-controlled relation with the other two machines.

In the operation of the system, only one operator is needed, this operator feeding the sheet to the first stamping press and controlling machines A and B through the foot treadle. In normal operation, the blanks will be fed automatically from the first machine into successive operative position in the second machine; and will also be fed 70 from the second machine to the third machine and dropped in the chute thereof, so that the work goes ahead automatically except for the control of one workman. One or more workmen are thus dispensed with, 75 as well as the hand transfer of the blanks. In actual operation, the machine saves considerable labor and cost.

The machines may be placed otherwise than in the rear of each other, as shown, 80 since the chutes may extend in different directions, the air blast being arranged accordingly. The operations of the successive presses may be other than those shown; 85 other sheet metal articles may be formed; and other changes may be made without departing from the spirit of my invention.

I claim:

1. A press system having at least two press devices provided with a common control for stopping and starting, and a channel arranged to lead the blanks from one machine to the next, and an air blast device for removing a blank from one of the press devices and delivering it to said channel substantially as described.

2. A stamping machine having a die and a die plunger a channel arranged to lead blanks to a position between its dies, and a movable support for the blanks arranged to check the movement of the delivered blanks, center the blanks and be automatically displaced when the plunger moves, substantially as described.

3. A press arranged to cut annular material from a blank, the press having a mandrel provided with a stationary knife cutter arranged to underlie and support the annular scrap and successively cut the annular scrap material into separated pieces upon the accumulation on the mandrel of a predetermined amount of scrap, substantially as described.

4. A press system having a plurality of presses arranged to act in succession on a blank, a common control for starting and stopping said machines, a channel leading from one machine to the next, and an air blast arranged to direct and deliver the blanks from the first machine into the channel, substantially as described.

5. A system for forming sheet metal caps, having a plurality of operating stations and a screw-threading station arranged in series, means for automatically ejecting the blanks

from the operating mechanism at the various stations and feeding the blanks from one station to the next by air pressure, and means at one of said stations for stripping the blanks substantially as described.

6. A machine system for making screw-threaded caps, comprising a plurality of operating stations and a threading station arranged in series, automatic mechanism for ejecting the blanks from the operating mechanism at the stations and feeding the blanks from one station to an operative position at the next station and from the last operating station to the threading station, and means at one of said stations for stripping the blanks substantially as described.

7. A sheet metal press having means for operating on a blank, an automatic feed for said press, and means having a fixed mounting relatively to the press for stopping a blank delivered by said feed and supporting the blank in position to be operated upon by said first mentioned means, said second mentioned means stripping the blank from the press after press action thereon, substantially as described.

8. A sheet metal press having means for

operating on a blank, a movable holding device having a fixed mounting relatively to the press and adapted to receive and hold a blank independently of said means, and a feeder arranged to feed successive blanks into the holding device, the holding device also acting to strip the blank from said means after action thereon, substantially as described.

9. A feeder for sheet metal presses, comprising a chute, a resiliently mounted holder in alignment with said chute and having lower supporting means and upper centering means, and means for feeding a blank through said chute into said holder, substantially as described.

10. A feeder for sheet metal presses, comprising a chute, a swinging holder in alignment with said chute and having resiliently mounted lower supporting means and upper centering means, and means for feeding a blank through said chute into said holder, substantially as described.

In testimony whereof I have hereunto set my hand.

PAUL J. SMITH.
